UNITED STATES PATENT OFFICE.

HARRY A. HOKE, OF ALTOONA, PENNSYLVANIA.

LOCOMOTIVE THROTTLE-VALVE

1,219,945.

Specification of Letters Patent.

Patented Mar. 20, 1917.

Application filed May 19, 1916. Serial No. 88,507.

To all whom it may concern:

Be it known that I, HARRY A. HOKE, a citizen of the United States of America, and a resident of Altoona, in the county of Blair and State of Pennsylvania, have invented a certain new and useful Improvement in Locomotive Throttle-Valves, of which the following is a true and exact description, reference being had to the accompanying drawings, which form a part thereof.

My present invention relates to throttle valves especially devised for use on railway locomotives, and particularly to throttle valves of the type comprising a main 15 throttle valve and a balancing cylinder and relief or pilot valve to facilitate the operation of the main throttle valve. One object of my invention is to provide a simple and effective throttle valve of the type referred 20 to having operating means which are adapted to be connected to and actuated in the usual manner by the ordinary throttle lever arrangement heretofore standard with the ordinary locomotive throttle valve not provided with a balancing cylinder and pilot valve.

Another object of my invention is to provide a valve of the type described of such construction that the movable valve parts 25 may be withdrawn from the valve body for cleaning, inspection, or repairs, with comparative ease and without requiring the valve body to be detached from the steam pipe to which it is normally connected.

The various features of novelty which characterize my invention are pointed out with particularity in the claims annexed to and forming a part of this specification. For a better understanding of the invention, 40 however, and the advantages possessed by it, reference should be had to the accompanying drawings and descriptive matter in which I have illustrated and described a preferred embodiment of my invention.

Of the drawings:

Figure 1 is a side elevation partly in section of the throttle valve mechanism proper;

Fig. 2 is an end elevation of the mechanism shown in Fig. 1;

Fig. 3 is a diagrammatic plan of a portion of a locomotive equipped with my improved throttle valve mechanism;

Fig. 4 is an elevation of a detail of the throttle valve operating mechanism;

Figs. 5, 6 and 7 are sections taken on the

lines 5—5, 6—6, and 7—7 respectively of Fig. 4; and

Fig. 8 is a view taken similarly to Fig. 1 showing a portion of a slightly modified construction.

In the drawings A represents the throttle valve casing or body proper which is open at its upper end and is formed at its lower end with an elbow like portion clamped in the usual manner to the end of the dry pipe A¹⁰ of the locomotive. The casing or valve body A is formed with an internal horizontal web or flange A' located somewhat below the upper end of the valve body and having a central opening or port A² through it. Fitting in the opening A² is a removable valve seat ring or annular member B which, as shown, has an out-turned flange at its upper end seated against the web A' at the margin of the port A². The valve seat ring is held against displacement by the stud bolts B' which are tapped into the web A', and the heads of which extend over the upper edge of the valve seat ring B. In the construction shown in Fig. 1, a slight clearance is provided between the periphery of the member B and the surrounding wall of the web A', and between the top of the member B and the heads of the bolts B'. This permits the member B a limited capacity for self-adjustment. Where this capacity is not needed or desired the seat member B may fit singly in its seat as shown in Fig. 8. In this case the upper edge of the valve seat ring B may be slightly above the upper surface of the web A' so that the valve seat ring B may be rigidly clamped against its seat by the bolts B'. The main throttle valve C is adapted to seat at its edge against the upper end of the valve seat ring B and is formed with a central passage C', and with a valve seat at the upper margin of this passage against which the valve seat engaging shoulder D' of a pilot valve D is adapted to bear in the closed position of the valve.

Within the valve body A and beneath the web A' is located a pressure equalizing cylinder A³, which is open at its upper end and closed at its lower end and integrally connected to the outer shell of the valve body as by the webs A⁴. The cylinder A³ which is coaxial with the port A² has an internal diameter slightly smaller than the diameter of the port A² proper, and slightly larger than

- the internal diameter of the valve seat ring B. Working in the cylinder A³ is a piston E formed as shown, on its upper side with a hollow open ended boss E' which has a telescopic connection with a hollow boss C² depending from the under side of the main valve C and surrounding the lower portion of the passage C'. The pilot valve D has a depending stem portion passing downward through the passage C' and through the hollow boss E', and carrying at its lower end a nut D² adapted to engage a hub or spider portion E³ of the valve member E in which the lower end of the stem of the pilot valve is guided. A small port E² through the piston E establishes a restricted communication between the lower end of the cylinder A³ and the surrounding portion of the outlet chamber of the throttle valve casing or dry pipe 20 on the outlet side of the port A².
- With the construction described, in the closed position of the throttle valve mechanism described, the main valve C seats against the valve seat ring B and the valve seat engaging portion D' of the pilot valve seats snugly against the seat provided at the upper margin of the passage C', and the main and pilot valves are held firmly against their seats by the steam pressure above them.
- The main valve is operated through the pilot valve D. The initial upward opening movement of the pilot valve D opens the upper end of the passage C' and permits the inlet pressure to pass into the lower end of the chamber A³ through the hollow boss E' of the piston E. This brings about the slight initial upward movement of the piston E necessary to bring the latter into engagement with a shoulder formed for the purpose on the main valve C, whereupon the downward pressure of the steam on the upper side of the valve C is substantially balanced, or slightly overbalanced, by the upward pressure acting on the under side 40 of the piston E. In consequence the main valve C may be manipulated with comparative ease.
- The means which I have devised for raising and lowering the pilot valve D and hence the main valve C, comprises a rocking or crank element G journaled on the valve body at its upper end. As shown, the crank or rocking element G is in the form of a rock shaft extending across the open upper end 55 of the valve body and journaled in split bearings A⁵ provided at the upper end of the valve body. The rock shaft G is provided with a central arm G², the free end of which is connected by the pivot pin G' to the upper end of a link F which is connected at its lower end by the pivot pin D⁴ to the pilot valve D, and extends in approximate alignment with the latter. At its ends the rock shaft G is provided with arms G³ 60 which are located at opposite sides of the valve body and are connected, as by the readily removable pivot pins G⁴, to the upper ends of depending links H. The latter are connected by pivot pins J⁰ to the arms J' of a rocking element J which is pivotally connected to the valve body.
- As shown, the rocking element J is formed with pockets J² open at one side to receive bracket ears A⁶ carried by the valve casing A and apertured to receive the bolt I on which the rocking element J is journaled. To facilitate the formation of the element J by casting, the latter is formed with a central passage which loosely receives the bolt I, and is open at one side for most of its length as is shown by the drawings. This permits the ready removal of the core material. This central passage is restricted at the side walls of the pockets J² to form cylindrical bearings, which may be reamed or bored out, for the bolt I. The member J is formed at its center with a crank arm J³ pivotally connected to the valve operating rod K. The latter passes through a stuffing box K' in the rear end wall of the locomotive boiler shell L and externally of the latter is connected to the usual throttle lever M, as shown diagrammatically in Fig. 3.
- The construction described thus permits of a simple and effective operating connection 95 between a throttle lever of the usual type and mounted in the usual location, and a throttle valve of the special balancing cylinder and pilot valve type shown. The character of the operating connections provided 100 for the pilot and hence the main valve, permit of a convenient and satisfactory construction of the internal portions of the throttle valve mechanism proper. The location of the main valve seat at a distance below the upper end of the valve body where the upper rocking element G is journaled, minimizes the tendency of the main valve and attached balancing piston to cock and jam in its guideway.
- The throttle valve mechanism proper is easily taken apart for inspection, adjustment or repairs. This may be conveniently and readily accomplished without disconnecting the valve body A from the steam pipe A¹⁰ when the cover L² for the steam dome L' is removed by proceeding in the following manner: First the valve C is moved to the wide open position and then the pivot pins G⁴ are removed. To facilitate the removal of the latter the upper edge of the valve body A may be notched as indicated at A⁹. After the rock shaft G is disconnected from the links H, the caps of the split bearings A⁵ are unbolted and removed, 115 and the bolts B' are taken out. When this is done, the rock shaft G, valves C and D, piston E, and valve seat ring B may all be drawn together away from the valve body A and out of the locomotive boiler shell 120 125 130

through the open top of the steam dome. The ease with which the throttle valve mechanism can thus be taken apart is of considerable practical importance, especially as this 5 operation frequently has to be performed while the locomotive is hot and sometimes where ordinary machine shop facilities are not available.

The location of the rocking element *J* at 10 the lower end of the valve body permits the operating rod *K* to be located well below the boiler shell while at the same time the throttle valve body is permitted to extend well up into the steam dome *L'* of the locomotive, 15 and the port controlled by the valve *C* may be located near the upper end of the valve body. The throttle valve operating mechanism offers a minimum of obstruction also to the inspection and repair of the interior 20 of the locomotive boiler through the steam dome *L'* when the cover *L²* is removed since neither the rock shafts *G* and *J*, nor the links *H* extend into the space between the rear of the valve body *A* and the adjacent 25 side wall of the steam dome *L'*.

While in accordance with the provisions of the statutes I have illustrated and described the best form of my invention now known to me, it will be apparent to those 30 skilled in the art that changes can be made in the form of my invention without departing from its spirit, and that some features of my invention can be used without a corresponding use of other features.

Having now described my invention, what 35 I claim as new and desire to secure by Letters Patent, is:

1. A locomotive throttle valve comprising in combination a valve body open at its upper end and provided with an internal ported valve seat below said upper end, a valve movable toward and away from said seat to control said port and operating means for said valve comprising an upper rocking element, means for journaling said element on said valve body above the valve seat made separable to permit the element to be lifted up and away from said valve body, a lower rocking element external to said valve body 50 and pivotally connected to the latter adjacent the lower end of the valve body, links external to the valve body connecting said rocking elements, and an operating connection to the lower rocking element.

55 2. In a locomotive, the combination with the boiler shell of a throttle valve located in said shell and comprising a valve body open at its upper end and provided with an internal ported valve seat below said upper end, a valve movable toward and away from said seat to control said port and operating means for said valve mounted on said valve body and comprising an upper rocking element, means for journaling said element on 60 said valve body above the valve seat made

separable to permit the element to be lifted up and away from said valve body, a lower rocking element external to said valve body and pivotally connected to the latter adjacent the lower end of the valve body, links external to the valve body connecting said rocking elements, and an operating rod connected to the lower rocking element and projecting through the rear end wall of said shell. 75

3. A locomotive throttle valve comprising in combination a valve body open at its upper end and provided with an internal ported valve seat below said upper end and a balancing cylinder located in the valve body 80 below said seat, a main valve movable toward and away from said seat to control said port, a balancing piston working in said cylinder, a pilot valve mounted in said main valve with freedom for limited movement relative to the latter and controlling communication with the interior of said cylinder below the balancing piston and valve operating means comprising a rocking element pivotally connected to said pilot valve, 85 means for journaling said element on said valve body above the valve seat made separable to permit the element to be lifted up and away from said valve body, and means external to and pivotally connected to said valve body adjacent the lower end of the latter for oscillating said rocking element. 90

4. A locomotive throttle valve comprising in combination a valve body open at its upper end and provided with an internal ported valve seat below said upper end and with external bracket ears at its lower end, a valve movable toward and away from said seat to control said port and operating means for said valve comprising a rock shaft, means for journaling said element on said valve body above the valve seat made separable to permit the element to be lifted up and away from said valve body, a second rock shaft journaled in said ears and 100 extending beneath the valve body, links at the sides of the valve body connecting said rock shafts and an operating rod pivotally connected to the lower rock shaft. 105

5. A locomotive throttle valve comprising in combination a valve body open at its upper end and formed internally with a seat for a valve seat member below said upper end and beneath said seat with a balancing cylinder and provided at its upper 115 end with separable shaft bearings, a removable annular valve seat member mounted in said seat, a main valve for controlling the passage through said annular seat member and a balancing piston working in said cylinder and of a diameter greater than the internal and less than the external diameter of said seat member, a pilot valve mounted in said main valve for controlling communication with said cylinder below the bal- 120 125 130

ancing piston, said piston and main and pilot valves being connected together with freedom for a limited relative movement of the two valves, a rock shaft mounted in said 5 bearings and extending across the valve body and a connection between said pilot valve and rock shaft.

6. In a locomotive, the combination with the boiler shell provided with a steam dome 10 and a removable cap for the latter, of a throttle valve comprising a valve body projecting up into the steam dome and open at its upper end and formed internally with a seat for a valve seat member below said 15 upper end and beneath said seat with a balancing cylinder, a removable annular valve seat member mounted in said seat, a main valve for controlling the passage through said annular seat member, a balancing piston working in said cylinder and of a diameter greater than the internal and less than the external diameter of said seat member, a pilot valve mounted in said main valve for controlling communication with said cylinder 20 below the balancing piston, said piston and main and pilot valves being connected together with freedom for a limited relative movement of the two valves, a rock shaft extending across the valve body above 25 said seat and means for journaling said shaft on said valve body made separable to permit the shaft to be lifted up and away from said valve body, a connection between said pilot valve and rock shaft, and actuating 30

means for said rock shaft mounted on said 35 valve body and detachably connected to said rock shaft.

7. A locomotive throttle valve comprising in combination with the boiler shell provided with a steam dome, of a throttle valve 40 located in said shell and comprising a valve body extending into the steam dome and having its center in front of the center of the steam dome, and being open at its upper end and provided with an internal ported 45 valve seat below said upper end and with a balancing cylinder located in the valve body below said seat; a main valve member moving toward and away from said seat to control the port in the seat and comprising a balancing piston working in said cylinder, a pilot valve mounted in said main valve with freedom for limited movement relative to the latter and controlling communication with said chamber and valve operating 50 means comprising a rocking element pivotally connected to said valve body at its upper end and a link connection between said rocking element and pilot valve, a second rocking element pivotally connected to the 55 valve body with its axis below the valve seat, means external to the valve body and located at the sides of the latter pivotally connecting said rocking elements, and an operating rod connected to said second rocking element and projecting through the rear 60 end wall of said shell.

HARRY A. HOKE.
